UNITED STATES PATENT OFFICE.

WALTER E. GRAVES, OF FLORISTON, CALIFORNIA.

PRESS FOR FORMING STEREOTYPE PLATES.

Application filed February 23, 1922. Serial No. 538,790.

To all whom it may concern:

Be it known that I, WALTER E. GRAVES, a citizen of the United States, and a resident of Floriston, county of Nevada, and 5 State of California, have invented a certain new and useful Improvement in Presses for Forming Stereotype Plates, of which the following is a specification.

My invention relates to manually operated presses for forming stereotype plates, so that they will be shaped to conform to the curve on the cylinder of the rotary printing press on which to be used.

One of the main objects of my invention 15 is to provide an improved press that will accurately and efficiently form the stereotype plates.

The presses which have heretofore been designed to do this work I consider to be 20 both unwieldy and inefficient, inasmuch as they are not adapted to permit the application of sufficient and accurate pressure.

I attain my object by providing pressure applying means, controlled by independent 25 levers—preferably operated by foot—which have different lever ratios.

Said presses usually comprise a frame provided with a fixed top piece, a piece or 30 table movable on the frame, and on which the stereotype plate is placed for forming; and devices are provided for moving the table against the top with sufficient force. As mentioned, the purpose of my invention is to provide efficient means for moving the 35 table against the fixed top.

My invention consists in providing a plurality of independent lever-like devices—for 40 example two foot levers—whereby the depression of one lever operates the table moving means with maximum speed but minimum force, and the depression of the other lever causes the slow application of the greater force for moving the table into that position which will effectively do the final 45 work of forming the plate.

The arrangement and operation of the devices by which I attain my object are shown in the accompanying drawings, in which:

50 Fig. 1 shows a side elevation of my improved press with a section of stereotype plate positioned between the dies;

Fig. 2 is an end view of my machine;

Fig. 3 is a cross sectional view taken on 55 the line 3—3 of Fig. 2;

Fig. 4 is a detail view taken on the line

4—4 of Fig. 1 and shows the action of the multiple foot levers; this detail showing the levers in their initial position when no pressure has been applied;

60 Fig. 5 is a detail view taken on the same line as Fig. 4 and shows the primary lever depressed;

Fig. 6 is a detail view on the same line as 65 4 and 5 and shows both primary and secondary levers depressed;

Fig. 7 is a detail view taken on the line 7—7 of Fig. 3 and shows how the compression member is positioned in the socket which is integral with the primary lever;

70 Fig. 8 is a detail view, partially sectional, of the primary lever; and

Fig. 9 is a detail view, partially sectional, taken on the line 9—9 of Fig. 1, of the secondary lever attached to the eccentrically 75 bored sleeve.

This machine is made up of side frames *a* and a fixed top *b* which is attached to the frames by means of tie rods *c*. The spacers *d* hold the head from the frames and also 80

serve as guides on which the movable table *e* can slide up and down. The top die *f* is removably secured to the fixed top *b* by means of a dovetailed joint *g*. The set screw *h* holds the top die *f* in place. The 85 lower die *i* is similarly attached to the movable table *e* by means of the dovetailed joint *j* and the set screw *m*. These dies are easily removed and thus a die of any desired curvature can be quickly and easily 90 locked into place. The lower die also provides a bearing in which the rod *k* can slide. The pusher *l* attached to the rod *k* is positioned so that the stereotype plate can be removed from between the dies by pulling the handle *k'* and thus it is not necessary to insert the hand between the dies. The 95 adjustable compression member *n* is pivoted between the ears *e'* and held between the bolt *e''*. The compression member can 100 be adjusted by means of the turn buckle *o* which moves on the threads *n'* of the compression member *n*. The threads *n'* are of opposite hands so that one turn of the turn buckle will shorten the compression member twice the pitch of the threads. The lock nuts *p* disposed on either side of the turn buckle prevent any movement when they are positioned against the turn buckle. The 105 lower end *h''* of rod *n* rests in the socket *q* which is offset from the axis of rotation of the hub of primary lever *r*. This primary

lever r consists of an arm and a hub r^2 . The eccentrically bored sleeve s is rotatively mounted on the fixed shaft t and within the hub r^2 . This eccentrically bored sleeve is attached to the secondary lever u by means of set screws u' . The notched rod v is held in engagement with the detent w by the detent spring x . This notched rod v has teeth v' formed in it which, when in engagement with the detent w , hold the primary lever in any desired position until it is manually released. The side frames a are held together by cross rods y , nuts y' , and washers y^2 and held apart by spacers z .

15 The action of the levers is as follows:

The levers are normally positioned as shown in Figs 1, 2 and 4. When the primary lever 7 is depressed it brings the socket q directly above the fixed shaft t and therefore as the socket is offset to the axis of rotation and positioned so as to be slightly before the dead center it follows that a stress will be put on the compression member which will cause the movable table to rise. This lever action has a relatively low lever ratio and so moves the two dies together speedily but without much pressure.

This action serves to take up the play between the dies and removes general irregularities of curvature. The secondary lever is attached to an eccentrically bored sleeve which revolves on the fixed shaft t . As previously mentioned, the hub of the primary lever rotates on the outer surface of this eccentrically bored sleeve. As the lever is depressed the compression member is given a small lift with the proportionally greater power and thus all the irregularities can be removed and thus a true, even and uniform curvature is obtained in the stereotype plate.

I claim:

1. In a press of the character described, having a frame, a fixed top and a table movable on the frame against said top, means for moving said table, comprising a shaft mounted in the frame, a sleeve having an eccentric bore rotatably mounted on said shaft, a primary lever provided with a hub rotatably mounted on said sleeve, a secondary lever rigid with said sleeve, a compression member connected at one end to said movable table and connected at its opposite end to the hub of said primary lever at a point offset from the axis of rotation of the hub of such lever, releasable, automatic means for holding said primary lever after depressed, said levers being adapted to apply relatively different ratios of speed and force to said table, so that thereby the latter may be quickly moved towards said fixed top by the operation of the primary lever, and then moved to its final position by greater force applied by the secondary lever.

65 2. In a press of the character described,

having a frame, a fixed top and a table movable on the frame against said top, means for moving said table, comprising a shaft mounted in the frame, a sleeve having an eccentric bore rotatably mounted on said shaft, a primary lever provided with a hub rotatably mounted on said sleeve, a secondary lever rigid with said sleeve, a compression member longitudinally adjustable, connected at one end to said movable table and connected at its opposite end to the hub of said primary lever at a point offset from the axis of rotation of the hub of such lever, releasable, automatic means for holding said primary lever after depressed, said levers being adapted to apply relatively different ratios of speed and force to said table, so that thereby the latter may be quickly moved towards said fixed top by the operation of the primary lever, and then moved to its final position by greater force applied by the secondary lever.

3. In a press of the character described, having a frame, a fixed top and a table movable on the frame against said top, means for moving said table, comprising a shaft mounted in the frame, a sleeve having an eccentric bore rotatably mounted on said shaft, a primary lever provided with a hub rotatably mounted on said sleeve, the hub being provided with a socket offset from the axis of rotation of the hub, a secondary lever rigid with said sleeve, a compression member connected at one end to said movable table and connected at its opposite end to the hub of said primary lever at a point offset from the axis of rotation of the hub of such lever, releasable, automatic means for holding said primary lever after depressed, said levers being adapted to apply relatively different ratios of speed and force to said table, so that thereby the latter may be quickly moved towards said fixed top by the operation of the primary lever, and then moved to its final position by greater force applied by the secondary lever.

4. In a press of the character described, having a frame, a fixed top and a table movable on the frame against said top, means for moving said table, comprising a shaft mounted in the frame, a sleeve having an eccentric bore rotatably mounted on said shaft, a primary lever provided with a hub rotatably mounted on said sleeve, a secondary lever rigid with said sleeve, a compression member connected at one end to said movable table and connected at its opposite end to the hub of said primary lever at a point offset from the axis of rotation of the hub of such lever, a rod connected to said primary lever, releasable automatic means adapted normally to lock the rod in the place to which moved by depressing said primary lever, said levers being adapted to apply relatively different

ratios of speed and force to said table, so that thereby the latter may be quickly moved towards said fixed top by the operation of the primary lever, and then moved 5 to its final position by greater force applied by the secondary lever.

5. In a press of the character described, having a frame, a fixed top and a table movable on the frame against said top, 10 means for moving said table, comprising a shaft mounted in the frame, a sleeve having an eccentric bore rotatably mounted on said shaft, a primary lever provided with a hub rotatably mounted on said sleeve, a 15 secondary lever rigid with said sleeve, a compression member connected at one end to said movable table and connected at its opposite end to the hub of said primary lever at a point offset from the axis of rotation of the hub of such lever, a notched rod connected to said primary lever, a 20 detent adapted for engaging the notches of said rod, and releasable automatic means adapted to throw said rod against said detent, said levers 25 being adapted to apply relatively different ratios of speed and force to said table, so that thereby the latter may be quickly moved towards said fixed top by the operation of the primary lever, and then moved 30 to its final position by greater force applied by the secondary lever.

6. In a press of the character described, having a frame, a fixed top and a table movable on the frame against said top, 35 means for moving said table, comprising

a shaft mounted in the frame, a sleeve having an eccentric bore rotatably mounted on said shaft, a primary lever provided with a hub rotatably mounted on said sleeve, the hub being provided with a socket offset 40 from the axis of rotation of the hub, a secondary lever rigid with said sleeve, a compression member longitudinally adjustable, connected at one end to said movable table and having its opposite end bearing in said 45 socket of said hub, a notched rod connected to said primary lever, a detent adapted for engaging the notches of said rod, and releasable automatic means adapted to throw said rod against said detent, said levers 50 being adapted to apply relatively different ratios of speed and force to said table, so that thereby the latter may be quickly moved towards said fixed top by the operation of the primary lever, and then moved 55 to its final position by greater force applied by the secondary lever.

7. In a press of the character described, having a frame, a fixed top and a table movable on the frame against said top, 60 means for moving said table, comprising a plurality of independent lever-like devices adapted to apply relatively different ratios of speed and force to said table, so that thereby the latter may be quickly 65 moved towards said fixed top by the operation of one lever, and then moved to its final position by greater force applied by another lever.

WALTER E. GRAVES.
